UNITED STATES PATENT OFFICE.

CHARLES BARTLETT BOSWORTH, OF EVERETT, ASSIGNOR TO THE CROSBY
STEAM GAGE AND VALVE COMPANY, OF BOSTON, MASSACHUSETTS.

GOVERNOR FOR HEATERS.

SPECIFICATION forming part of Letters Patent No. 473,056, dated April 19, 1892.

Application filed January 22, 1892. Serial No. 418,907. (No model.)

To all whom it may concern:

Be it known that I, CHARLES BARTLETT BOSWORTH, a citizen of the United States, residing at Everett, in the county of Middlesex 5 and State of Massachusetts, have invented certain new and useful Improvements in Governors for Open Feed-Water Heaters; and I do hereby declare the following to be a full, clear, and exact description of the invention, 10 such as will enable others skilled in the art to which it appertains to make and use the same.

Figure 1 represents the device attached for use. Fig. 2 is a section through the float-chamber, Fig. 1. Fig. 3 is a section through 15 the water-valve and governor, Fig. 1. Fig. 4 is a detail section.

This device is a governor for an open feed-water heater, and is attached to that class of heaters within which the water is not under 20 pressure before it is forced to the boiler through the pump employed. Such a heater is constructed to receive into or through it the exhaust-pipe of a steam-engine, and the water is warmed or heated either by coming 25 in contact with the large exhaust-pipe passing through it or by being projected in the form of a spray into the steam which enters it from the exhaust-pipe. It is important in either case that the water shall not rise above 30 a given point, as, if it does, it may flow into the end of the exhaust-pipe and so disturb the operations of the engine to which it would be conveyed. Heretofore the water has been controlled in its height by manipulation, on 35 the part of a man, of the water-valve, which supplies it with water either directly from a street-main or aqueduct or by a pump forcing it into the heater, observing the rise and fall of it through a gage-glass connected with 40 the heater. The present device is so perfect in its operation and control of the water supplied to the heater that the water-line once determined upon by its attachment to the heater does not vary in its rise and fall more 45 than half an inch.

In the annexed drawings, the letter A indicates an open feed-water heater having the water-supply pipe B, which comes from any source and enters the heater A above the wa- 50 ter-level. Passing into the heater A is the exhaust-pipe C from a steam-engine, and the

pipe C' is to lead hot water out. Attached to the heater is a float-chamber D, connected by the pipes d and d' with the heater A above and below the water-levels. This float-chamber has an angular enlargement d², in which is pivoted the stem e of a float E, which is in the main float-chamber. In the enlargement d², just above the stem e, is a valve-opening f, which is closed by a valve f', which rests 60 upon the float-stem e. From this valve-opening f a pipe F passes and is connected with the water-supply pipe B through a larger pipe or coupling G. Where the pipes F and G are connected together there is placed a dia- 65 phragm g, Fig. 4, having the perforation g'. In the pipe G is a valve g². Located in the pipe B, above the pipe G, is the ordinary wa- 70 ter-valve H, provided with its governor I. The stem h of the valve H passes out of the valve- casing and up into a chamber k of a box K, where it is headed and surrounded by a spring k', which bears between the head h' of the stem h and the bottom of the chamber k. The head h' of the stem h rests against a pis- 75 ton h², which in turn rests against a dia- phragm k², secured across the top enlarge- 80 ment k³ of the box K. Above the diaphragm k² the interior of the box K is connected by a pipe l with the pipe F.

Operation: The water is turned on by opening the positive valve M. As the water flows, it passes through the valve H and into the top of the heater. Water also passes through the valve g², pipe G, perforation g', and pipe F 85 into the float-chamber D. As the water rises in the heater, it also rises in the float-chamber. As the float E rises, its stem e gradually lifts the valve f' and closes the opening f. When this occurs, the water in the 90 pipe F flows through the pipe l, and, bearing upon the diaphragm k², depresses the valve H, closing it and cutting off the flow of wa- 95 ter to the heater. As the water falls in the latter, the valve f is opened and the valve H released. The perforation g' in the diaphragm g, being smaller in cross-section than the pipe, reduces the quantity or flow of water from the main pipe to the water-valve regulator and the float-chamber, so that the small valve 100 in the float-chamber will be sufficient to take care of it. It is only necessary to have just

enough fluid to reach the piston of the regulator of the water-valve as shall close the water-valve. Any more than that would not only be unnecessary, but would be troublesome.

5 Having thus described my invention, what I claim is—

1. The combination of a water-reservoir, its supply-pipe, a valve located in such pipe and provided with a governor, a float-chamber connected to and communicating with such reservoir and provided with a float, and a valve-opening provided with a valve, a pipe leading from such valve-opening and communicating with the water-supply pipe, and another pipe 10 leading from such last pipe to the water-valve governor, as set forth.
- 15 2. The combination of a water-reservoir, its supply-pipe, a valve located in such pipe and provided with a governor, a float-chamber connected to and communicating with such reservoir and provided with a float, and a valve-opening provided with a valve, a pressure-pipe leading to such valve-opening from a fluid under pressure and also connected with the water-valve governor, as set forth. 20

In testimony whereof I affix my signature in presence of two witnesses.

CHARLES BARTLETT BOSWORTH.
